No. 808,653.

PATENTED JAN. 2, 1906.

W. F. HALL & W. DONALDSON.

GARMENT HANGER.

APPLICATION FILED OCT. 11, 1900. RENEWED DEC. 17, 1904.

UNITED STATES PATENT OFFICE.

WILLIAM F. HALL AND WALTER DONALDSON, OF WASHINGTON,
DISTRICT OF COLUMBIA.

GARMENT-HANGER.

No. 808,653.

Specification of Letters Patent.

Patented Jan. 2, 1906.

Application filed October 11, 1900. Renewed December 17, 1904. Serial No. 237,293.

To all whom it may concern:

Be it known that we, WILLIAM F. HALL and WALTER DONALDSON, citizens of the United States, residing at Washington, District of Columbia, have invented certain new and useful Improvements in Garment-Hangers, of which the following is a specification.

Our invention relates more particularly to that class of garment-hangers which is designed to hold trousers suspended by gripping the bottoms of the legs of the same; and it consists in the special construction and arrangement of parts, as will be hereinafter fully described, and particularly pointed out in the claims.

In the drawings, Figure 1 is a perspective view of the invention; Fig. 2, a sectional view of the wedge-piece; Fig. 3, a detail view representing the manner of securing the metal clips in place, and Fig. 4 is a detail view representing another way of effecting the connection of the clips with the backboard. Figs. 5 and 6 are sectional views of modifications of our device.

The hanger is made up of a backpiece or board 1, of wood or like material, having slits 2 formed in its ends intermediate of its front and back faces and extending from the top to and through the bottom edge. The metal clips 3 are wedge-shaped, being provided with overhanging flanges 4, inclining upwardly toward the backboard and presenting wide mouths or openings at the lower part of the board to receive the wedge-piece 5, as will be herein-after more fully described.

The end clips or sockets for receiving the wedge-piece are provided with base-flanges 6, which extend into the slits in the ends of the backboard. We secure these metal sockets in place without the use of nails, screws, rivets, or the like, and for this purpose we form the sockets from sheet metal, which is capable of being indented or upset into the wood of the back-piece. We prefer to upset the metal by simply driving a punch through the wooden back-piece, so that the point thereof striking the sheet metal will indent or prick the same, and thus force it into the wood on the opposite side of the slit from that from which the punch is driven. This construction is shown in Fig. 3. The upset metal is indicated at 12 in Fig. 3. Instead of this the metal may be upset at its exposed edges, as shown at 7 in Fig. 4. In either case the upset part of the

metal will hold the metal clip in place securely, coacting for this purpose with the walls of the slit. The slit is of such width as to receive the metal snugly, so that the base-flange will be held firmly against movement toward the front and rear, and, further, the depth of the slot is such that the edge of the base-flange will abut squarely against the bottom of the slit, and it will be found that the metal need be indented only at one place, as this coöperating with the abutting edge of the flange will resist all tendency of the clip to turn in the slit. The wedge-piece is, like the backboard, made of wood, and it has an inclined front face, so that when it is inserted in the guides or sockets and moved upwardly therein its flat back face will move toward the goods resting upon the front face of the back-piece, and thus engage the garment.

The hanger is suspended by a hook 8, and this is secured in place by boring a hole through the wedge-piece at an inclination, so that the upper end of the hook will be over the center of gravity, or substantially so. For this purpose the hook extends substantially parallel with the front inclined face of the wedge-piece. This arrangement of the hook is shown in Fig. 2.

As shown in Fig. 2, the hook-shank is bent slightly at its lower end or upset to form a head, as at 9, and this is sufficient to sustain the weight of the parts. The wedge-piece can turn around the hook, so that the garment will swivel about its point of suspension.

As indicated in Fig. 4, the base-flange may be formed with a tongue α therein, (see dotted lines,) and after the base-flange is inserted a punch may be forced through the board to strike the tongue and embed it into the wood.

As shown in Fig. 5, the two parts of the hanger may be joined by a flexible connection 10. This connection may have the suspending device thereon, and the front portion of this flexible connection is preferably shorter than the rear portion, so as to place the front portion connected with the wedge-piece under strain when the parts are hung up. This flexible connection, as shown at 11 in Fig. 6, may be connected to the hook and to the back-piece. It will be seen that the slit in the piece 1 is of the same width throughout. It extends from edge to edge of the piece, and by this arrangement the slit can be quickly formed by presenting the ends of the piece to a saw.

A circular, band, or other saw can be used in forming the slits. The base-flange of the guide is plain and flat, and as the slit is also plain and of a width to receive the flange the 5 guide can be readily inserted from the end of the piece and pushed in until the edge of the base-flange finds a bearing against the bottom of the slit and the end wall γ of the guide finds a bearing against the end of the piece. 10 These bearings will prevent lateral rocking of the metal guide in the slit, and it then needs only a single indentation of the metal at, for instance, α to securely hold the guide in place. Another advantage of this construction is that the bearing of the end wall γ at 13 against the end of the slotted piece serves to brace the guide against inward displacement.

We claim—

1. A garment-hanger comprising a piece 20 having slits in its ends, extending from edge to edge of the piece and of the same size throughout, wedge-shaped guides having plain flat base-flanges fitted to said slits and held therein with the end wall of the guides extending from the slit up across the end of the slotted piece, and a piece arranged to slide in the guides to hold the garment.

2. In combination in a garment-hanger, a piece having slits at its ends, guide-pieces having a base-flange fitted to the slit, the metal of said base-flange being upset into the material of the slotted piece adjacent to the slit and a clamping-piece movable in the guide-pieces, substantially as described.

35 3. In combination in a garment-hanger, a

piece having slits at its ends, guide-pieces having a flange fitted to the slit with the edge of the flange bearing against the bottom of the slit, said flange being upset into the wood forming the wall of the slit intermediate of 40 its side edges, substantially as described.

4. In combination in a garment-hanger, a back-piece having slotted ends, guides having base-flanges inserted in the slits, the metal of the base-flange being punched through the 45 wooden back-piece from one side of the slit into the wood on the opposite side of the slit and a clamping member movable in the guides on the back-piece to clamp the garment between itself and the said back-piece, substantially as described.

5. In combination in a garment-hanger, a back-piece guides presenting wedge-shaped guideways and having a portion driven into the back-piece at or near its ends and a wedge 55 member movable in the guides to hold the garment.

6. In combination in a garment-hanger, a back-piece, guides presenting wedge-shaped guideways and having a portion inserted in 60 the back-piece intermediate the thickness thereof and a wedging member movable in the said guides, substantially as described.

In testimony whereof we affix our signatures in presence of two witnesses.

WM. F. HALL.
WALTER DONALDSON.
